UNITED STATES PATENT OFFICE.

FRANK L. FURBUSH, OF WESTFORD, MASSACHUSETTS, ASSIGNOR TO C. G. SARGENT'S SONS CORPORATION, OF GRANITEVILLE, MASSACHUSETTS, A CORPORATION OF MASSACHUSETTS.

IMMERSING DEVICE FOR WASHING BOWLS.

Application filed September 15, 1924. Serial No. 737,727.

To all whom it may concern:

Be it known that I, FRANK L. FURBUSH, a citizen of the United States, residing at Westford, in the county of Middlesex and 5 State of Massachusetts, have invented a new and useful Immersing Device for Washing Bowls, of which the following is a specification.

This invention relates to that type of machines for washing wool and other fibres in 10 which a rake is used for pushing the fibres along the bowl from one end to the other and for pushing them down so that the fibres will be subjected to the action of the 15 water and will be advanced intermittently.

The principal object of this invention is to provide means, controlled and guided in part by the rake, for ensuring that the fibres at a certain point or points along the rake 20 shall be thoroughly immersed under the surface of the water or other liquid in the bowl at least once during their travel along the bowl from end to end.

Reference is to be had to the accompanying 25 drawings, in which—

Fig. 1 is a side view of a washing bowl shown with a preferred embodiment of this invention applied thereto, the bowl being broken away to show interior construction;

30 Fig. 2 is a similar view showing the rake in a different position; and

Fig. 3 is a fragmentary plan of one side of the bowl and one end of the float.

As stated, the invention relates to a wool 35 washing machine comprising a long bowl containing the liquor into which the wool or other fibre is fed at one end and along which it is carried by the reciprocation of the rake 11 having teeth 12 extending down 40 into the liquor within the bowl. These parts of the ordinary type of wool washing machines are not changed by this invention but in addition thereto I place in the bowl and under the rake one or more floats 13. These 45 floats are located between two sets of rake teeth and extend across the bowl. They are designed to float on top of the liquor in the bowl as shown in Fig. 1 when the rake is raised and to be forced down into the liquor 50 when the rake is lowered as shown in Fig. 2.

The object is to thoroughly immerse all the fibres as they pass the point at which the float is located. The machine can be made with only one of these floats because

all the fibres pass each point and they will 55 all be forced down in at that point if only one of them is used, but I prefer to employ a plurality as indicated in Fig. 1.

In construction this float preferably is a water-tight roll cylindrical in shape al- 60 though it can be of other shapes. It can be made of solid wood or of hollow metal filled with ground cork or any material that will float. I prefer to make it cylindrical so that it will roll along freely on the water with- 65 out resistance to the rake, but that is not es- sential.

At the sides of the bowl are a pair of supports or guides 14 each having two vertical end walls and an inclined bottom wall. 70 These are for receiving the ends of the roll or studs thereon as desired and they support the roll when the liquor is drawn off. The bottom is made inclined so that the roll will find its proper location when the rake is 75 drawn up or the liquor drawn off and when the rake comes down on it, it will slide one way or the other and the rake will not puncture it.

In the operation of the device, when the 80 rake goes down the parallel rails at the top, which constitute the back of the rake, push the roll down into the liquor and also carry it along the full travel of the rake. When the rake moves back on the return motion, it also carries the roll back still in the liquor. If in coming down the rake teeth strike the roll it will roll along on the liquor one way or the other enough to avoid puncture. When the liquor is drawn off the roll will 90 rest on the bottom of the guides 14 and roll down to the lowest point and then will float when the liquor is introduced. These guides represent the limit of the downward travel of the roll but they do not interfere with it 95 as they are made deep enough to avoid that difficulty.

Although I have illustrated and described only a single form of the invention I am aware of the fact that modifications can be 100 made therein by any person skilled in the art without departing from the scope of the invention as expressed in the claims. Therefore I do not wish to be limited to all the details of construction herein shown and 105 described but what I do claim is:—

1. In a washing bowl, the combination with the bowl and a reciprocating rake

therefor, of a float in the bowl located between two sets of teeth of the rake in position to be moved down into the liquor in the bowl by the descent of the rake and to be moved along the bowl by its reciprocation.

2. In a machine for washing wool or the like, the combination with a bowl and a reciprocating rake, of a cylindrical float located at a point between two sets of teeth of the rake in a position to float and to be pushed down into the liquor by the descent of the rake.

3. In a wool washing machine, the combination with a bowl having guides at its sides and a reciprocable rake, of a float adapted to float on the liquor in the bowl and having its ends extending into said

guides to be guided thereby, whereby when the rake descends it will push the roll down into the liquor and carry it along to immerse any stock in that vicinity and whereby when the liquor is drawn off the roll will remain in the guides ready for use.

4. In a wool washing machine, the combination with a bowl having guides at its sides and a reciprocable rake, of a float adapted to float on the liquor in the bowl and having its ends extending into said guides to be guided thereby, said guides comprising vertical ends and an inclined bottom.

In testimony whereof I have hereunto affixed my signature.

FRANK L. FURBUSH.
